UNITED STATES PATENT OFFICE.

HERMON W. HOWARD, OF WASHINGTON, DISTRICT OF COLUMBIA.

STRIP-MOISTENING MACHINE.

1,156,687.

Specification of Letters Patent.

Patented Oct. 12, 1915.

Application filed September 28, 1914. Serial No. 863,942.

To all whom it may concern:

Be it known that I, HERMON W. HOWARD, a citizen of the United States, residing at Washington, in the District of Columbia, have invented certain new and useful Improvements in Strip-Moistening Machines; and I do hereby declare the following to be a full, clear, and exact description of the invention, such as will enable others skilled in the art to which it appertains to make and use the same.

The present invention relates to strip moistening machines, and consists more particularly in strip moistening machines of the type embodying a roll of tape supplied with an adhesive, which is arranged to be drawn over a moistening roller and brought into contact with a knife mounted on the machine for severing the strip into the required lengths.

It is an object of the present invention to provide a strip moistening machine, the framework of which is constructed of sheet metal, and of few and simple parts, economical of manufacture and adapted for ready assembly to constitute the machine.

Another object of the present invention resides in providing a strip moistening machine which will be conveniently portable and at the same time embody sufficient weight to maintain the same steady during the operation of severing the prepared strip; and to this end the machine is built upon a relatively heavy bed and provided with a detachable bail whereby the same may be readily transported.

In the accompanying drawings forming a part of this application, and in which similar reference symbols indicate corresponding parts in the several views: Figure 1 is a side elevational view of a strip moistening machine constructed in accordance with the present invention. Fig. 2 is a rear elevational view of the same. Fig. 3 is a front elevational view of the same. Fig. 4 is a vertical sectional view of the machine as shown in Fig. 1. Fig. 5 is a horizontal sectional view taken on the line 5—5 of Fig. 4; and Fig. 6 is a similar view taken on the line 6—6 of Fig. 4.

Referring more particularly to the drawings, wherein one embodiment of the present invention is illustrated, 1 designates a bed, which I have found convenient to construct of wood as giving the necessary weight to maintain the machine stable during opera-

tion; although I do not wish to be limited to the same, as the bed may be advantageously constructed of other suitable material.

Erected upon the bed 1 is the frame 2 of the machine, the same being preferably constructed of sheet metal bent into substantially rectangular form and having the edges thereof overlapped and riveted, or otherwise secured, as indicated at 3. From the frame 2 are bent flanges 4 for resting upon the bed 1, and the flanges 4 are arranged to be confined in position by means of a base plate 5 secured to the top of said bed.

As will appear more clearly from Figs. 2, 3 and 5, the frame 2 is cut away, as indicated at 6, to provide a pair of oppositely disposed standards 7 and 8 of channel construction, and the edges of the same are overturned, as at 9, to impart strength and rigidity to the same and present a smooth and finished appearance. Between the standards 7 and 8 a strip roll 10 is arranged to be rotatably journaled, and to this end the roll 10 is wound upon a core 11, the latter being arranged to be removably fitted over a hollow spindle 12 journaled in bearings in the standards 7 and 8, as will be understood.

For convenience in lifting the machine and transporting the same, a bail 13 is provided, constructed preferably of a single length of spring metal bent substantially rectangular, and having its free ends in-turned and adapted to be sprung into the projecting hollow ends of the spindle 12. Such an arrangement, in addition to furnishing a handle, further assists to maintain the spindle 12 in position and positively prevents the accidental endwise withdrawal of the same from the bearings in the frame standards. Above the cut-away portion 6 the frame is slotted, as indicated at 14 and 15, at the front and rear walls respectively; and the edges of the frame, as illustrated, are overturned to provide guide means for the strip 10, as advantageously shown in Fig. 4. The rear wall of the frame above the slot 15 is bent over to provide a top 16, extending to the forward wall where the edge thereof is turned downwardly and bolted, riveted, or otherwise secured, as indicated at 17, to the forward wall of the frame.

Referring to Figs. 2 and 4, both the rear wall and top 16 of the frame are, intermediate the sides thereof, severed, and the severed portions bent respectively horizontally,

as at 18, and vertically, as at 19, to provide a recess for the reception of a holder 20, provided with overturned flanges 21 for resting upon the upper edges of the top 16 of the frame and facilitating positioning and removal of the same.

As indicated in Fig. 6, the holder 20 is perforated to receive a spindle 22 on which is journaled an absorbent moistening roller 23. The moistening roller 23 rotates in a receptacle 24 positioned within the holder 20 and secured against displacement by the ends of the spindle 22. The receptacle 24 is supplied with water or an adhesive fluid which is transferred to the strip 10 by means of the roller 23, over which the former is drawn by the operator, as will be apparent from Fig. 4. The strip 10 may be drawn out to the required length and severed by means of a serrated or other knife 25, constructed integral with the forward wall of the frame and looped rearwardly, as indicated at 26, to provide a resilient support therefor, whereby the shock of the severing movement may be partially absorbed and prevented from transmission totally to the frame which would otherwise tend to upset the latter. Arranged to operate with the guide slots 14 and 15 is a plate 27 constructed with a right angularly disposed and overturned lower end 28, and perforated at its upper reduced end for the passage of a tensioning screw or bolt 29 threaded into the front wall of the frame, as indicated. The plate 27 bears upon the strip 10 in its passage to the guide slot 14, assisting to properly direct the same and at the same time imposing tension thereupon to prevent the strip from being too freely unwound. In order to prevent the liquid in the receptacle 24 from overflowing or spilling upon the prepared strip 10, I provide a guard 30 constructed with flanges 31 for embracing the sides of the roll and with a shank 32 bent to form a hook 33 freely engaging over a bar, located below the guide slot 14, for pivotally supporting the same.

In operation, the roll of prepared strip coiled upon the core 11 is inserted between the standards 7 and 8, and the hollow spindle 12 passed through the alined openings in the standards and core whereby the roll is removably mounted for rotary movement therein. The bail 13 is thereupon sprung over the projecting hollow ends of the spindle 12 and the same prevents accidental withdrawal of said spindle. The end of the strip roll 10 is threaded through the alining guide slots 14 and 15, the plate 27 being revolved about its pivot 29 to give free access to the same, and the strip is carried upwardly and forwardly over the roller 23, whereby the adhesive upon the strip is moistened. The strip 10, as will be understood, may be drawn out to the required

length and quickly severed by a downward movement of the strip into engagement with the knife 25. After the severing operation, the strip between the slot 15 and the knife 25 will furnish an end sufficiently long to be conveniently grasped for succeeding use.

I have illustrated and described preferred and satisfactory constructions, but obviously changes could be made in the herein described apparatus which could be used without departing from the spirit of my invention.

I claim:

1. In a portable strip moistening machine, the combination of a frame, a spindle journaled in said frame, a bail arranged to engage the opposite ends of said spindle, a strip roll mounted on said spindle, a moistener supported in said frame and arranged in the path of said strip, and a knife supported in proximity to said moistener for severing the strip, substantially as described.

2. In a portable strip moistening machine, the combination of a frame, a hollow spindle journaled through said frame, a bail provided with inturned ends arranged to detachably engage the projecting hollow ends of said spindle, a strip roll mounted on said spindle, a moistener supported in said frame and arranged in the path of said strip, and a knife located in proximity to said moistener for severing the strip, substantially as described.

3. In a portable strip moistening machine, the combination of a frame provided with a recess therein, a hollow spindle removably journaled in said frame, a bail provided with inturned ends arranged to detachably engage the hollow projecting ends of said spindle, a strip roll mounted on said spindle, a moistener for the strip comprising a container fitted in the recess in said frame, a spindle mounted in said container and arranged with its ends projecting to engage the adjacent walls of the frame whereby to maintain the container in position, and an absorbent roll mounted on said spindle and revolving in said container, and a spring-mounted knife located in proximity to said moistener for severing the strip, substantially as described.

4. In a strip moistening machine, the combination of a frame constructed of sheet metal arranged substantially rectangular in cross section and provided with a vertical cut-away portion dividing the frame to provide a pair of channelled uprights, said frame being provided with slots in spaced relation above said vertical cut-away portion, a strip roll removably journaled between said channelled uprights and having the free end of the strip threaded through said slots, a tensioning plate secured to said frame, means for varying the tension there-

of, a moistener supported in said frame in the path of the strip, and a spring-mounted knife constructed integral with the frame and arranged to sever the strip, substantially as described.

5. In a portable strip moistening machine, the combination of a weighted base, a frame erected substantially centrally on said base and constructed of sheet metal arranged 10 substantially rectangular and formed with a vertical cut-away portion dividing the frame to provide a pair of vertical uprights, a hollow spindle removably journaled through said uprights, a bail formed with 15 inturned ends detachably engaging the hollow projecting ends on said spindle, a moistener supported in said frame and in the path of the strip, a guard plate mounted over said strip roll and extending beneath 20 the moistener, and a spring-mounted knife located on said frame in proximity to the moistener for severing the strip, substantially as described.

6. In a portable strip moistening machine, 25 the combination of a weighted base, a frame erected substantially centrally on said base and constructed of sheet metal arranged rectangular and formed with a cut-away portion dividing the frame to provide a 30 pair of channeled uprights, said frame be-

ing further provided with guide slots above said cut-away portion and a recess above said guide slots, a spindle removably journaled in said channeled uprights, a bail provided with inturned ends detachably engaging the projecting ends of said spindle, a strip roll mounted on said spindle, the strip being threaded through said guide slots, a tension plate removably connected with said frame, means for varying the tension of said plate, a moistener comprising a container removably fitted in the recess in said frame, a spindle journaled in said container and provided with projecting ends 45 engaging the adjacent walls of the frame for maintaining the container in position, and an absorbent roll mounted on said spindle, a guard plate mounted in said frame and embracing the strip roll below said moistener, and a spring-mounted knife 50 formed integral with the frame in proximity to the moistener for severing the strip, substantially as described.

In testimony whereof, I affix my signature, in presence of two witnesses.

HERMON W. HOWARD.
